UNITED STATES PATENT OFFICE

2,610,605

AUTOMATIC AIR PAINTING UNIT WITH
TRANSVERSE OSCILLATING ACTION

Jens A. Paasche, Chicago, Ill.

Application July 30, 1948, Serial No. 41,584

14 Claims. (Cl. 118—7)

1

This invention is directed generally to continuous aircoating devices for coating a surface with paint or other material, and more specifically, to an oscillating mechanism to be used with aircoating equipment.

In certain types of continuous aircoating processes, oscillating devices are used in combination with endless work conveyors. Certain of the oscillating devices now employed use a plurality of complex parts, many of them costly, to accomplish the desired results. These devices do not lend themselves readily to repair. Furthermore, many of these devices do not ensure an even aircoating stroke which is so essential in this type of work. In addition, many of these devices waste paint or other coating material by spraying during part of the time that the workpiece is not under the spray guns or nozzles.

Therefore, one object of this invention is to provide a simple oscillating device wherein a minimum number of well-known parts is used in a novel manner to obtain an oscillating motion, the simplicity reducing cost of manufacture and facilitating maintenance of the device.

It is another object of this invention to provide a portable and adjustable oscillating mechanism which may be used with a plurality of machines where such motion is desired.

It is a further object of the present invention to provide an oscillating device which operates with equal facility in a horizontal or vertical position.

It is still another object of the present invention to provide an oscillating mechanism which has an even stroke in both directions during the oscillating operation and wherein the speed of oscillation is readily controlled.

It is still a further object of the present invention to provide an oscillating mechanism which is adapted to be used with various sized units, the unit having means for adjustably locking the oscillating mechanism in the desired position relative to the unit.

It is an object of the improved form of this invention to provide an oscillating mechanism with an improved valve control which is adapted to use a minimum amount of paint or other coating material by causing the airbrushes to cut out and cut in at exactly the same position regardless of the speed of oscillation.

These and many other important objects of the invention will be more clearly understood upon reading the following detailed description and reference to the accompanying drawings wherein:

Figure 1 is a side view of a continuous aircoat-

2

ing device showing the oscillatory unit in combination with a conveyor platform and hood;

Figure 2 is a sectional view of the oscillatory unit and conveyor taken along the line 2—2 in Figure 1;

Figure 3 is a top view of the oscillatory unit taken along the line 3—3 in Figure 2;

Figure 4 is a sectional view through the carriage and support taken along the line 4—4 in Figure 3;

Figure 5 is a front view of the speed control mechanism for the unit taken along the line 5—5 in Figure 3;

Figure 6 is an end view of the motor for driving the oscillating unit and the mounting therefor taken along the line 6—6 in Figure 3;

Figure 7 is a front view of the carriage previously disclosed in Figure 2;

Figure 8 is a cross sectional view of the carriage taken along the line 8—8 in Figure 7;

Figure 9 is a front view of a carriage similar to Figure 7 of an improved form of the invention including also part of the transverse supporting structure;

Figure 10 is a side view, part in section, of the carriage and support of the improved form of the invention taken along the line 10—10 in Figure 9;

Figure 11 is a top view of the carriage and gun structure of the improved form of the invention taken along the line 11—11 in Figure 9;

Figure 12 is a sequence drawing of the operation of the valve control cams and followers in the improved form of the invention;

Figure 13 is a side view, part in section, of one of the cams controlling the valve in the improved form of the invention;

Figure 14 is a sectional view of the cam disclosed in Figure 13 taken along the line 14—14 in Figure 13; and

Figure 15 is a sectional view of the valve in the improved form of the invention.

Referring now to the drawings more in detail wherein like reference numerals are used to indicate similar parts throughout the various figures, it will be seen that the oscillatory unit contemplated by the instant invention is designated generally by the numeral 10. This oscillatory unit 10 is shown in combination with other elements which together comprise an automatic aircoating device. These elements include a conveyor platform 12 having legs 14 adapted to support side members 16. Sprocket wheels 18 and 20 are mounted at opposite ends of side members 16 on axles 22 and 24, respectively, and mounted in bushings, (not shown), supported by said side

55 in bushings, (not shown), supported by said side

members. Depending arms 26 and 28 are fixed to side members 16 in any convenient manner and adapted to serve as mounting means for axles 30 and 32 on which sprocket wheels 34 and 36 are mounted, respectively, in a fashion similar to sprocket wheels 18 and 20. An endless chain 38 is mounted about the periphery of these sprocket wheels 18, 20, 34 and 36. Another set of sprocket wheels, (not shown), with a chain 41, best seen in Figure 2, is mounted on the other ends of shafts 22, 24, 30 and 32 in a fashion similar to wheels 18, 20, 34 and 36. Rods 43 are mounted between chains 38 and 41 to provide a platform on which work 39 may be carried into the air-coating hood 40. These chains 38 and 41 may be driven at the required speed by a sprocket wheel on one of the axles connected to a drive means.

Hood 40 is provided to overlie the conveyor platform. Details of the hood will best be understood by a reference to my co-pending application Serial No. 545,812. The hood is comprised of a body portion 42 with openings, (not shown), provided over the conveyor platform 12 to permit entrance of the work 39 therein. Window 44 is provided in one wall of the body portion to permit the operator of the device to view the work and is preferably designed in a manner so as to permit access to the interior of the hood by the operator.

Oscillating unit 10 is comprised of a pair of standards 46 and 47 adapted to rest on the floor on their bases 48. Upright body portions 49 and 51 of standards 46 and 47, respectively, are adapted to telescopically receive arms 50 and 52. Clamp members 53 and 55 are provided adjacent the ends of body portions 49 and 51 for positioning arms 50 and 52 at any desired height. Joining the ends of the two arms 50 and 52 is a support member or track 54 preferably of tubular construction. Spaced at a predetermined distance below support member 54 is a second support member 56 attached at its opposite ends by means of clamp members 58 and 60. Clamp members 58 and 60 also support a shelf 62, best seen in Figure 3, on which is mounted the driving mechanism, later to be described.

A carriage 63, best seen in Figures 2, 4, 7 and 8, is comprised of two side plates 64 and 66. These side plates are properly spaced relative to each other at their uppermost ends by means of axles 68 and 70 which pass through both plates, shoulders being provided on the axles near their ends to engage the inner surface of the side plates 64 and 66. Threads provided adjacent the ends of the axles accommodate nuts for clampingly engaging the plates 64 and 66 therebetween. Wheels 72 and 74 are rotatably mounted on arms 68 and 70, respectively, and adapted to lie on track member 54. Adjacent the bottom of the side plates 64 and 66 a U-shaped member 76 is secured to the side plates to hold them in predetermined spaced relation to each other. Adjacent the bottom of the side plates, and on either side of the U-shaped member 76, are mounted housings 78, 82, 83 and 85 which are secured in any convenient manner. Vertically arranged axles 84 and 86 have their opposite ends journaled in the walls of the housings. Wheels 88 and 90 are rotatably mounted on axles 84 and 86, respectively, the wheels in housings 83 and 85 not being shown in the drawings. A third set of wheels 92 and 94 are mounted adjacent the upper end of side plate 64 immediately below wheels 72 and 74, heretofore described. These wheels are mounted in housings 96 and 98 on

axles 100 and 102, respectively. Wheels 72 and 74 carry the weight of carriage 63 and wheels 88, 90, 92 and 94 prevent horizontal shifting of the carriage.

5 Mounted on the exterior of side plates 64 are two vertically arranged strips of material 104 and 106. These strips of material 104 and 106 may be attached to the side plate in any convenient manner, such as welding, bolts or the like. Strips 104 and 106 form a channel or track which is adapted to coact with the drive mechanism later to be described.

The carriage 63 is adapted to carry a plurality of brackets for mounting equipment to be reciprocated. Figures 7 and 8 show an arm 112 attached at its one end to the U-shaped bracket 76 and adapted to telescopically receive another arm 114 at its other end to provide an adjustable and extensible mounting for airbrushes or spray guns 116 to be clamped thereon. A C-shaped clamp 117 adjacent the end of arm 112 permits retention of arm 114 in any desired position. Also mounted on the carriage is bracket 118 to which is secured a valve 120 for controlling the supply of air to the airbrushes 116. The valve 120 comprises inlet means 122, outlet means 124 and a valve needle 126. Spring arm 128 is pivotally mounted adjacent the valve needle 126 in its extended position by means of a screw or the like 130. At the other end of spring arm 128 are flanges 132 with a roller wheel 134 mounted therein. Conduits 136 from paint container 138 may also be mounted on the side plates of the carriage as shown in Figure 8. For purposes of disclosure these conduits are mounted in a pair of collars 140 and 142 adapted to be mounted on opposite sides of side plate 66 and to retain the coupling 144 in rigid position relative to the carriage 63.

40 For operating the valve 120 during oscillation of carriage 63, a pair of stops 137 and 139 are provided. These stops are comprised of C-clamps 141 and 143 adapted to be secured to arms 52 and 50, respectively. Integral with the clamps are clamp members 145 and 147 which are adapted to receive arms 149 and 151 telescopically therein. Adjacent the ends of arms 149 and 151 are cam surfaces 153 and 155, respectively, which are adapted to engage the roller wheel 134 of arm 128, whereby valve 120 is closed during the period of engagement with the arms 149 and 151. Thus, by this simple mechanism, the spraying period of the airbrushes or other means controlled by valve 120 may be controlled.

55 The driving mechanism for oscillating the carriage 63 comprises a pair of right-angle brackets 146 and 148 mounted on shelf 62, previously described, by means of shoulders 150. Sprocket wheels 152 and 154 are rotatably mounted on the upright flange of brackets 146 and 148, respectively. An endless chain 156 is mounted over the periphery of these two sprocket wheels. A stud or arm 157 is mounted on the chain 156 and extends laterally outwardly from the chain. Adjacent its free end a small wheel 159 is rotatably secured. This stud member 157 is adapted to lie in the channel formed by strips 104 and 106 on the carriage and to transmit the reciprocatory movement of the chain to the carriage. The shaft 155 of sprocket wheel 154 is extended through the upright flange wall of bracket 148 and adapted to be positively engaged by a speed reducer unit 158. A motor 160 is slidably mounted on a support shown generally at 162 which comprises a plurality of shafts 164 on which the

base 166 of motor 160 is slidably mounted, as seen best in Figure 5. Adjacent the ends of the shafts is a plate 168 on which a wheel 170 is supported. Plate 168 is provided with an aperture 172 through which the threaded shaft 174 of wheel 170 passes. The walls of aperture 172 in plate 168 act as a bearing for the end portion 176 of the threaded shaft 174. The threaded portion of shaft 174 is received in a complementary threaded aperture 178 of the base 166 and serves to lower and raise motor 160 relative to the shelf 62. On motor shaft 180 is mounted a pulley wheel 182 having a V-shaped periphery. A V-shaped belt 184 is adapted to be positioned in the V-shaped periphery of wheel 182 and over wheel 186, operatively connected to the speed reducer 158. The position of belt 184 in the V-shaped periphery of wheel 182 may be altered by raising or lowering the position of the motor 160 relative to the shelf 62, thus varying the speed of speed reducer 158.

The operation of the oscillating mechanism 10 may be described substantially as follows: Upon actuation of motor 160 the speed reducer 158 is driven at a desired speed which in turn drives chain 156. Chain 156 with its stud or arm 157 and rotatable wheel 159 engages the walls of the channel formed by strips 104 and 106 on the carriage, thereby driving the carriage 63 in the direction of the chain. As the direction of stud 157 is reversed, after traversing the periphery of sprocket wheel 152 or 154, the stud shifts vertically in the channel formed by strips 104 and 106 and reverses the direction of movement of the carriage 63. Obviously, the distance the carriage 63 moves along tracks 54 and 56 is always the same, but the length of the spraying stroke is readily controlled by the adjustable cam arms 149 and 151, heretofore described.

In the improved form depicted in Figure 9, the vertical support member 50a is topped by hemispherical cap 190 which may be formed integral with support 50a or attached in any desirable fashion. Formed integral with support 50a are bosses 192 and 194 in which horizontal support members 54a and 56a are held by hexagonal nuts 196, 197, 198 and 199 threaded onto threads cut in the ends of supports 54a and 56a. Vertical support members 50a and 52a, (the latter not shown), carry adjustable cam mounting rod supports 201 and 203, (not shown), held on by C clamps 204, (not shown), and 206. Cam mounting rods 200 and 202 fit telescopically within supports 201 and 203 and are held by clamps 205, (not shown), and 207. Half of each C clamp may be formed integral with its associated cam mounting rod support or may be attached thereto by any suitable means. Clamp 206 is held together and can be adjusted vertically by means of bolts 208 which may be secured by nuts or may be threaded into the C clamp. Clamp 204 is secured to support member 52a in a like manner and is not shown. On the cam mounting rods 202 and 200 are mounted cams 210, 212, 214 and 216, the action of which will be described subsequently. Each cam is individually adjustable horizontally and is held in place by a set screw such as 218 seen in Figures 13 and 14.

Carriage 63a is like carriage 63 previously described except as noted. It is comprised of two castings 64a and 66a fastened together at their top ends by axles 68a and 70a as in the earlier disclosure of carriage 63. The plate 220 is mounted on the side of carriage 63a by stud

bolts 222 which are threaded into casting 66a. The valve 120a for controlling the supply of air to the airbrushes 116a is mounted on plate 220. The valve 120a comprises inlet means 122a, outlet means 124a, a valve stem 126a and valve head 127. Arm 128a is pivotally mounted adjacent the valve control member 126a by means of a screw or the like 130a. A roller wheel 134a bears on the other end of arm 128a. The roller wheel 134a is held in the bifurcated upper portion of a pivoted double action cam following member 224. The cam following member 224 includes the fingers 224a, 224b and 224c which contact the cams 210, 212, 214 and 216 in a manner to be described later.

An air line 226 is connected at one end to outlet means 124a and to a conduit 228 which passes through the bottom of carriage 63a and on which are threaded nuts 230 and 232 which serve to hold the two pieces of carriage 63a together at the bottom. This pipe then leads to the airguns. A conduit 234 carrying paint may also be held on carriage 63a by any desirable means, (not shown), and also leads to the air-guns.

Valve 120a is open only when cam following member 224 is in an essentially vertical position to cause its roller 134a to push up on arm 128a which in turn holds up valve stem 126a and head 127. When cam follower 224 pivots about its mounting stud 225, spring 129 pressing against nut 131 forces stem 126a and head 127 down to shut off the valve until arm 128a is again raised to force the valve open. As all the cams are constructed similarly, only the construction of cam 214 is described. Cam 214 consists of non-rotating portion 215 slidably mounted on cam mounting rod 200 and held in place by set screw 218. Side plates 214a and 214b are held together by and pivot about bolt 217 on which is threaded nut 219. Side plates 214a and 214b carry roller 221 on rivet 223 which also serves to hold the side plates together. Side plates 214a and 214b are rotatable 90° to the left about bolt 217 but are normally held in an upright position by spring 213.

Figure 12 shows a sequence action depicting the cam mechanism operation. In position A the carriage is first moving to the right with the valve open. As finger 224b strikes the roller 221 of cam 214, cam follower 224 is pivoted to the position shown at B and valve 120a closes. As finger 224c strikes the roller of cam 216, it causes the pivotable part of cam 216 to pivot to the right as shown in dotted lines at D without altering the position of cam follower 224. The action of the spring causes the pivoted portion of cam 216 to return immediately to its normal vertical position. After carriage 63a reaches its furthermost position to the right and starts back, finger 224c encounters the roller of cam 216. As the pivotable portion of cam 216 will not pivot to the left, cam follower 224 is returned to a vertical position as shown at C thus opening the valve 120a. When finger 224b encounters the roller 221 of cam 214, it causes the pivotable portion of cam 214 to pivot to the left as shown in dotted lines at A without altering the position of cam follower 224. The pivoted portion of cam 214 is then returned to its normal vertical position by the action of spring 213 and the carriage continues to the left where its cam follower 224 meets cams 212 and 210 with similar results. Evidently the opening and closing of the valve at different points will operate to

save a considerable quantity of paint or other material.

As a result of this invention an oscillating mechanism may be inexpensively produced, and by reason of its simple construction, readily repaired when the occasion demands.

Furthermore, the oscillating carriage of the unit is driven at a uniform rate of speed, which speed may be controlled as desired. This uniformity of action is essential where spraying apparatus is to be associated therewith in order to insure even distribution of material sprayed on objects passing therebeneath. By reason of the ability to control the speed of oscillation it is possible to use this unit with many different machines having movable platforms which move at various rates of speed.

While in the foregoing paragraphs and accompanying drawings, two of the preferred embodiments of the invention have been disclosed, it is to be understood that these disclosures are for purposes of description only, and that the invention shall be limited only by the scope of the appended claims.

The invention is hereby claimed as follows:

1. An oscillatory mechanism comprising a track mounted on a support, a carriage translatablely mounted on said track, a valve member mounted on said carriage, said valve member including a valve stem and a valve head, shoulder means on said carriage for engaging a stud member, individually adjustable means vertically displaced only slightly from the line of movement of said valve stem and valve head and mounted at each end of said track for operating said valve member, and means for oscillating said carriage including continuous drive means mounted over the periphery of a plurality of wheels, means to rotate said wheels, and a stud member mounted on said drive means and coacting with said shoulder means on said carriage for imparting an oscillatory movement thereto upon rotation of said wheels.

2. An oscillatory mechanism comprising a track mounted on a support, a carriage translatablely mounted on said track, a valve member mounted on said carriage, said valve member including a valve stem and a valve head, means on said carriage for engaging a stud member, individually adjustable cam arms mounted at each end of said track and displaced vertically only slightly from the line of movement of said valve stem and valve head for operating said valve member, and means for oscillating said carriage including continuous drive means mounted over the periphery of a plurality of wheels, a variable speed drive mechanism adapted to rotate said wheels, and a stud member mounted on said continuous drive means imparting an oscillatory movement to said carriage as said continuous drive means is driven over the periphery of said wheels.

3. An oscillatory mechanism comprising a track mounted on a support, a carriage mounted on said track, a valve member mounted on said carriage, a pivotally mounted spring arm mounted on said carriage adjacent said valve member for operating said valve member, means on said carriage for engaging a stud member, adjustable cam arms mounted at each end of said track for engaging said spring arm to operate said valve member, and means for oscillating said carriage including continuous drive means mounted over the periphery of a plurality of wheels, a variable speed drive mechanism for driving said wheels, and a stud member on said drive means adapted

to engage said stud engaging means on said carriage to oscillate said carriage as the endless belt is driven over the periphery of said wheels.

4. In a continuous aircoating device including an endless conveyor for carrying work to be air-coated, said conveyor being mounted on a support, an oscillatory unit arranged transversely of said conveyor and comprising a translatablely mounted carriage on a support, means for causing said carriage to oscillate back and forth, a plurality of airbrushes mounted on said carriage, a valve mounted on said carriage for controlling the operation of said airbrushes, a plurality of cams fixed adjacent each extremity of operation, and a double acting cam follower mechanism in the form of a spider with a plurality of fingers thereon actuated by said cams, said cam follower mechanism controlling said valve as said carriage is oscillated transversely of said conveyor.

5. In a continuous spraying device including an endless conveyor for carrying work to be sprayed and an oscillatory unit arranged transversely of said conveyor and comprising a translatablely mounted carriage on a support, means to oscillate said carriage in timed relationship with said conveyor, and a plurality of spray guns mounted on said carriage, means for controlling the operation of said spray guns comprising a pair of individually adjustable cam arms mounted on the carriage support, a pivotally mounted spring arm carried on said carriage, a valve member mounted on said carriage adjacent said spring arm, said spring arm engaging said adjustable cam arms during oscillation of said carriage and operating said valve for controlling the operation of the plurality of spray guns.

6. An oscillatory unit for mounting spray guns comprising a support, a carriage translatablely mounted on said support, means for causing said carriage to oscillate upon said support, a spray gun mounted on said carriage, a valve mounted on said carriage for controlling the operation of said spray guns, a pair of cams fixed adjacent each extremity of the path of travel of said carriage, and a double acting cam follower mechanism mounted on said carriage and actuated by said cams, said cam follower mechanism controlling said valve as said carriage is moved on said support, one of said cams at each end of said path of travel serving to move said cam follower mechanism to the inoperative position and the other of said cams serving to move said cam follower mechanism to the operative position.

7. In a spraying device including an oscillating carriage and a spray gun mounted thereon, a valve mounted on the carriage for controlling the operation of the air gun, a pair of cams mounted adjacent one end of the path of travel of said carriage, and a double acting cam follower mechanism mounted on the carriage and actuated by said cams, said cam follower mechanism controlling said valve as the carriage is oscillated, one of said cams at the end of said path of travel serving to move said cam follower mechanism to the inoperative position and the other of said cams serving to move said cam follower mechanism to the operative position.

8. An oscillatory mechanism comprising a support, a track mounted on said support, a carriage translatablely mounted on said track, means for oscillating said carriage upon said track, a spray gun, a valve mounted on said carriage for controlling the operation of said spray gun, a pair of cams fixed adjacent each extremity of the

path of travel of said carriage, and a double acting cam follower mechanism mounted on said carriage and actuated by said cams, one of said cams actuating said cam follower mechanism when the carriage moves in one direction, and the other of said cams actuating said cam follower mechanism when the carriage returns in the other direction.

9. An oscillatory mechanism as set forth in claim 8 wherein said cams are individually and independently adjustable with respect to each other and the support.

10. In an oscillatory mechanism including a support, a track mounted on the support, a carriage translatable mounted on the track, a spray gun mounted on the carriage, and means for oscillating said carriage upon said track, a spray gun actuating and controlling mechanism comprising a valve for controlling the actuation of the spray gun, a plurality of cams mounted adjacent each end of the path of travel of said valve at the extremities of the path of travel of said carriage, and a double acting cam follower mechanism mounted in a fixed position with respect to said valve and adapted to be actuated by said cams, said cam follower mechanism controlling said valve as the carriage is oscillated.

11. In an oscillatory mechanism including a support, a track mounted on the support, a carriage translatable mounted on the track, a spray gun mounted on the carriage, and means for oscillating said carriage upon said track, a spray gun actuating and controlling mechanism comprising a valve for controlling the actuation of the spray gun, a plurality of cams mounted adjacent each end of the path of travel of said valve at the extremities of the path of travel of said carriage, and a double acting cam follower mechanism in the form of a spider with a plurality of fingers thereon actuated by said cams, said cam follower mechanism controlling said valve as the carriage is oscillated.

12. In a spraying device including an oscillating carriage and a spray gun mounted thereon, a valve mounted on the carriage for controlling the operation of the spray gun, a pair of cams mounted adjacent one end of the path of travel of said carriage, a line interconnecting said cams being substantially parallel to the path of travel of said carriage, and a double acting cam follower mechanism mounted on the carriage and

actuated by said cams, said cam follower mechanism controlling said valve as the carriage is oscillated, the cam positioned outwardly with respect to the path of travel of said carriage being effective to move said cam follower mechanism to the spray initiating position, the cam positioned inwardly along the path of travel of said carriage being effective to move said cam follower mechanism to the spray interrupting position.

13. An oscillatory mechanism comprising a support, a track mounted on said support, a carriage translatable mounted on said track, means for oscillating said carriage upon said track, a spray gun, a valve mounted on said carriage for controlling the operation of said spray gun, a pair of cams fixed adjacent each extremity of the path of travel of said carriage, said cams being arranged in a line substantially parallel to the path of travel of said carriage, and a double acting cam follower mechanism mounted on said carriage and actuated by said cams, the outermost cam of each pair of cams being effective to move said cam follower mechanism to the spray initiating position, the innermost cam of each pair of cams being effective to move said cam follower mechanism to the spray interrupting position.

14. An oscillatory mechanism as set forth in claim 13, wherein said cams are individually and independently adjustable with respect to each other and the support.

JENS A. PAASCHE.
